HYDRAULIC JAR

Wayne N. Sutliff, Bakersfield, Calif.

Application August 6, 1951, Serial No. 240,487

4 Claims. (Cl. 255—27)

1

This invention relates to an oil well tool and particularly to a hydraulic well jar of the type including a hammer and anvil, in which the hammer is retarded when urged toward the anvil to tension the drill string or wire supporting the well jar, and then released to cause a violent impact between the hammer and anvil. The present application is a continuation-in-part application of my prior co-pending application entitled, "Hydraulic Well Jar and Method of Use," Serial No. 49,973, filed September 18, 1948, now abandoned.

As is well known to those skilled in the art, well jars are connected to twisted off strings of drill pipe and other objects that become lodged or stuck in well bores for the purposes of jarring the lodged or stuck members in an effort to loosen them for removal.

Hydraulic well jars of the type described above have the advantage of being simple in construction, including few parts, and wearing less rapidly than mechanical well jars. However, these hydraulic well jars have not been dependable in operation, in many instances functioning for only a few jars and then ceasing to operate properly, necessitating their removal and adjustment or repair. I believe that this defect in operation is caused by the creation of voids in the hydraulic fluid chamber in the well jar. I believe that these voids detrimentally affect the operation of such a well jar by preventing the extent of retardation of the hammer necessary to sufficiently tension the drill string or wire line to cause a violent impact between the hammer and anvil upon release of the hammer. These voids may be formed or created in several ways. The hydraulic fluid chamber may not be entirely filled when the well jar is prepared for use. The high internal hydraulic pressures created in the well jar on the high pressure side of the hammer during operation may cause leakage past the packing on the high pressure side, or leakage can occur past the other packing in the well jar.

It is a main object of the present invention to provide a hydraulic well jar having a hydraulic fluid chamber including a compensating floating piston exposed on one side to the pressure of the well fluid and on the opposite side to the low pressure side of the hammer, so that when the well jar is lowered into a well, the pressure of the well fluid will cause the floating piston to shift under the influence of a differential pressure created by the voids or leaking fluid and thereby reduce the volume of the hydraulic fluid chamber to where the volume thereof is equal to the hydraulic fluid therewithin, whereby existing voids in the hydraulic fluid chamber are eliminated and the

2

formation of new voids causable by leakage of hydraulic fluid from the chamber is prevented. This floating compensating piston structure is disclosed in my prior co-pending application above identified.

Another object of the present invention is to provide an improved hydraulic well jar, particularly one having an improved valve arrangement. The valve arrangement of the present application, though being broadly similar to, is specifically different from the one shown in my prior identified co-pending application.

Various other objects will be apparent from the following description taken in connection with the accompanying drawings, wherein:

Fig. 1 discloses a well jar embodying the concepts of the present invention being shown in quarter section.

Fig. 2 is an enlarged sectional view, through a portion of the well jar disclosed in Fig. 1, showing the valve closed and the hammer in the process of being pulled upwardly toward the anvil.

Fig. 3 is a view, similar to Fig. 2, showing the hammer after having been released and in engagement with the anvil.

Fig. 4 is a view, similar to Fig. 2, showing the hammer being moved downwardly and the valve being open.

Fig. 5 is a view showing the manner of attachment of the hydraulic well jar to a wire line.

Referring to the accompanying drawings wherein similar reference characters designate similar parts throughout, the hydraulic well jar has a hydraulic fluid chamber formed by a valve housing 9, which has a lower sub 11 secured to the lower end thereof, and an upper sub 13 secured to the upper end of valve housing 9. This hydraulic fluid chamber is filled with a suitable hydraulic fluid, such as oil, through ports 14 in valve housing 9 closed by pipe plugs 14a.

A central composite mandrel 15 extends through the hydraulic chamber and, adjacent its upper end, sealingly engages upper packing 17, carried by upper sub 13, and, adjacent its lower end, sealingly engages lower packing 19, carried by lower sub 11. Above lower packing 19, there is a floating compensating annular piston 21 slidably received within valve housing 9 and slidably receiving the lower end of composite mandrel 15. The hydraulic fluid is therefore contained within tubular housing 9 and upper sub 13 and between upper packing 17 and floating piston 21. Further reference to the floating compensating piston 21 will be made hereinafter.

Upper packing 17 is adapted to be held in place by a packing nut 23 threadedly received within the upper end of upper sub 13, and lower packing

19 is held in place by a lower packing nut 29, threadedly received within the lower end of lower sub 11.

Composite mandrel 15 includes an upper mandrel section 31 having a hammer 33 formed thereon adapted to violently strike an anvil 35 formed on and depending from upper sub 13. The upper mandrel section 31 is keyed at 37 to upper sub 13 to provide a rotary drive with the outer tubular assembly which is adapted to be secured to a lodged twisted off string of drill pipe, casing or fish within a well bore. Upper mandrel section 31 slidably extends through the packing nut 23 and is threadedly attached by its upper end 25 to the lower end of a drill string 27.

Valve housing 9 is interiorly formed with a small bore 39, slidably receiving a valve 41 carried by the lower end of upper mandrel section 31, and an enlarged bore 43, into which valve 41 is adapted to be moved to release hammer 33. At its lower end, upper mandrel section 31 is threadedly connected to a lower tubular mandrel section 45, said lower tubular mandrel section having an upwardly facing valve seat 47 thereon. A compression spring 49 contained within a counter bore 51 formed on valve 41 urges the valve into engagement with valve seat 47. The exterior of the lower end of the upper mandrel section 31 is grooved at 53 to provide passageways to allow the fluid to bypass valve 41 when the valve is disposed off its seat. It is pointed out that the grooves 53 terminate at a point spaced slightly above the valve seat 47 to ensure that the pressure above the hammer 33 is not effective on the under side of valve 41.

The functioning and operation of the parts described up to this point are as follows: Fig. 1 shows the position of the parts when valve 41 is disposed in small bore 39 of valve housing 9, and under these conditions an upward pull on the composite mandrel 15 will cause the mandrel to move upwardly. Since valve 41 is seated, the fluid above the hammer 33 is trapped and can move downwardly only by passing between the exterior of valve 41 and the bore 39. This creates a tension in the drill string and, when the valve 41 clears the bore 39, the hammer 33 is released and therefore instantly moves up and violently strikes the anvil 35, therefore jarring the fish or stuck member to which the outer tubular assembly is connected.

Thereafter, the drill string is moved downwardly so as to move the hammer assembly, including valve 41, into the small bore 39 of the valve housing 9. When this occurs, the fluid below the hammer 33 is trapped and a small pressure is created which, being effective on the seat side of valve 41, will cause the valve to move upwardly compressing spring 49 and therefore allowing the trapped fluid to pass through grooves 53 and thereby bypass valve 41. The pressure created under these conditions below the hammer 33 is only sufficient to overcome the resistance of the spring 49, which is not large.

The operation above described results in repeated violent impacts between the hammer and anvil. However, if voids exist or are created within the hydraulic fluid chamber the operation of the hydraulic well jar becomes erratic and the hydraulic well jar does not function properly. Under these conditions, the only recourse is to replace the jar with another, which is an expensive and time consuming operation.

Voids may be formed in the hydraulic fluid chamber in several ways, as previously men-

tioned. In the present invention, voids existing in the well par at the time the well jar is lowered into the well are eliminated and future voids causable by leakage of well fluid from the well jar are prevented from being formed by the floating compensating piston 21. The floating compensating piston is normally initially positioned, as shown in Fig. 1, against a rest 55 provided by the lower sub 11, but is allowed to move upwardly under the influence of a differential pressure to always maintain the volume of the hydraulic fluid chamber equal to the volume of the hydraulic fluid within the chamber. This movement of floating compensating piston 21 is effected by providing a plurality of ports 57 in lower sub 11 to expose the bottom side of the piston 21, as the parts are depicted in the drawings, to the pressure of the well fluid. If voids originally exist in the hydraulic fluid chamber of the well jar before the well jar is lowered into the well, these voids will be eliminated when the well fluid, entering through ports 57, will urge the piston upwardly to maintain the volume of the hydraulic fluid chamber equal to the volume of the fluid therein. Furthermore, if during the operation, leakage of the hydraulic fluid from the well jar occurs, a commensurate decrease in pressure of the hydraulic fluid will occur and therefore result in a differential pressure effective to move the piston upwardly and to maintain the volume of the hydraulic fluid chamber equal to the volume of the hydraulic fluid therewithin, therefore preventing the formation of voids in the hydraulic fluid chamber.

Fig. 5 shows a construction wherein the composite mandrel 15 is connected to a wire line 61 by a wire line socket 63, instead of being connected to a drill string, as shown in Fig. 1.

By the present invention, a well jar has been provided which will be repeatedly effective to give a succession of violent jars, and in which well jar the hydraulic fluid chamber will be maintained at a volume equal to the volume of the hydraulic fluid therewithin, therefore preventing the formation or existence of voids which hinder the operation of the well jar.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A hydraulic well jar, comprising a hollow fluid-tight housing adapted to be secured to a fish lodged in a well and providing a hydraulic fluid chamber defined in part by a large bore portion and a small bore portion, an anvil within the large bore portion of the housing, a mandrel adapted to be reciprocated by a drill string or wire line and slidably received within the housing and carrying a hammer adapted to be brought into violent contact with the anvil, an annular valve on the mandrel dimensioned to slidably fit within the small bore and over the mandrel and being operable to retard movement of the hammer toward the anvil when the valve is disposed within the small bore portion of the housing to cause tensioning of the drill string or equivalent structure and to suddenly release the hammer when moved to a position within the large bore portion of the housing to allow the hammer to violently strike the anvil, said mandrel having a

valve seat formed thereon facing axially toward the anvil and fluid passageways formed on the outer surface of said mandrel inwardly of the valve for bypassing the valve when the valve is unseated, said passageways extending from a point beyond the valve seat toward the hammer and beyond the valve and being closed by the valve against fluid passage past the valve seat when said valve is closed, spring means urging the valve toward its seat to seal off the passageways, and a floating compensating annular piston slidably received by the chamber and slidably receiving the mandrel, exposed on one side to the pressure of the hydraulic fluid in the chamber and on its opposite side to the pressure of the well fluid, operable, when the well jar is lowered into a well and the piston is subjected to the well fluid pressure, to eliminate existing voids in the hydraulic fluid chamber and prevent the formation of new voids, causable by leakage of hydraulic fluid from the chamber, by shifting under the influence of a differential pressure created by the voids or leaking fluid to reduce the volume of the hydraulic fluid chamber to an extent where the volume of the hydraulic fluid chamber is equal to the volume of the fluid therewithin.

2. A hydraulic well jar, comprising a hollow fluid-tight housing adapted to be secured to a fish lodged in a well and providing a hydraulic fluid chamber defined in part by a large bore portion and a small bore portion, an anvil within the large bore portion of the housing, a mandrel adapted to be reciprocated by a drill string or wire line and slidably received within the housing and carrying a hammer adapted to be brought into violent contact with the anvil, an annular valve on the mandrel dimensioned to slidably fit within the small bore and over the mandrel and being operable to retard movement of the hammer toward the mandrel when the valve is disposed within the small bore portion of the housing to cause tensioning of the drill string or equivalent structure and to suddenly release the hammer when moved to a position within the large bore portion of the housing to allow the hammer to violently strike the anvil, said mandrel having a valve seat formed thereon facing axially toward the anvil and fluid passageways formed on the outer surface of said mandrel inwardly of the valve for bypassing the valve when the valve is unseated, said passageways extending from a point beyond the valve seat toward the hammer and beyond the valve and being closed by the valve against fluid passage past the valve seat when said valve is closed, and spring means urging the valve toward its seat to seal off the passageways, and a floating compensating annular piston slidably received within the chamber at a point to be exposed to the pressure on the side of the hammer remote from the anvil, and slidably receiving the mandrel, and exposed on its opposite side to the pressure of the well fluid, operable, when the well jar is lowered into a well and the piston is subjected to the well fluid pressure, to eliminate existing voids in the hydraulic fluid chamber and prevent the formation of new voids, causable by leakage of hydraulic fluid from the chamber, by shifting under the influence of a differential pressure created by the voids or leaking fluid to reduce the volume of the hydraulic fluid chamber to an extent where the volume of the hydraulic fluid chamber is equal to the volume of the fluid therewithin.

3. In a hydraulic well jar of the type having a hydraulic fluid chamber reciprocably receiving

a mandrel, and wherein a hammer is provided on one of the parts in axial alignment and adapted to be brought into violent engagement with an anvil provided on the other of the parts upon relative movement between the chamber and mandrel in one direction, means for trapping fluid in the space between the hammer and anvil operable to suddenly release the fluid to effect a sudden movement of the hammer toward the anvil, the improvement which comprises the provision of a passageway communicating the interior of the chamber with the exterior thereof, and an annular floating piston surrounding the mandrel and dimensioned to snugly fit against the interior walls of the chamber and on the mandrel to seal against both members, said piston being exposed on one side to the pressure of the hydraulic fluid in the chamber and on its opposite side to the pressure of the well fluid and being operable when the jar is lowered into a well and the piston is subjected to the well fluid pressure, to eliminate existing voids in the hydraulic fluid chamber and prevent the formation of new voids, causable by leakage of hydraulic fluid from the chamber, by shifting under the influence of differential pressure created by the existing voids or by leaking fluid to reduce the volume of the hydraulic fluid chamber to an extent where the volume thereof is equal to the volume of fluid therewithin.

4. In a hydraulic well jar of the type having a hydraulic fluid chamber reciprocably receiving a mandrel, and wherein a hammer is provided on one of the parts in axial alignment and adapted to be brought into violent engagement with an anvil provided on the other of the parts upon relative movement between the chamber and mandrel in one direction, the improvement which comprises the provision of a passageway communicating the interior of the chamber with the exterior thereof, an annular resilient floating piston surrounding the mandrel and dimensioned to snugly fit against the interior walls of the chamber and on the mandrel to seal against both members, said piston being exposed on one side to the pressure of the hydraulic fluid in the chamber and on its opposite side to the pressure of the well fluid and being operable when the jar is lowered into a well and the piston is subjected to the well fluid pressure, to eliminate existing voids in the hydraulic fluid chamber and prevent the formation of new voids, causable by leakage of hydraulic fluid from the chamber, by shifting under the influence of differential pressure created by the existing voids or by leaking fluid to reduce the volume of the hydraulic fluid chamber to an extent where the volume thereof is equal to the volume of fluid therewithin, and means for trapping fluid in the space between the hammer and anvil operable to suddenly release the fluid to effect a sudden movement of the hammer toward the anvil, said piston being located on the side of the hammer remote from the anvil so that it is not subjected to the extreme pressures created in the space between the hammer and the anvil.
